United States Patent Office

Des. 193,595
Patented Sept. 11, 1962

193,595

ANCHOR

John K. Northrop, Santa Barbara, and Eldon M. Wilson,
La Canada, Calif., assignors to The Garrett Corpora-
tion, Los Angeles, Calif., a corporation of California

Filed June 27, 1961, Ser. No. 65,723

Term of patent 14 years

(Cl. D71—1)

Fig. 1.

Fig. 2.

Fig.3.

FIG. 1 is a front elevational view of an anchor, showing our new design.

FIG. 2 is a side elevational view thereof, the opposite side, not shown, being substantially the same in appearance, and

FIG. 3 is a rear perspective view thereof.

We claim:

The ornamental design for an anchor, as shown and described.
